Primary Examiner — Caron D Veynar*Assistant Examiner* — Abraham Bahta*(74) Attorney, Agent, or Firm* — Christopher Wood; Premier Law Group(57) **CLAIM**

The ornamental design for a military data form, as shown and described.

DESCRIPTION

The FIGURE is a front view of a military data form showing my new design.

It being understood that the rear is flat and unornamented and the sides are of no substantial thickness. The outer rectangular broken lines shown in the FIGURE are for illustrative purposes only and form no part of the claimed design.
